RAY A. McHALE, OF SYRACUSE, NEW YORK, ASSIGNOR TO LOIS T. McHALE, OF SYRACUSE, NEW YORK.

ALIGNING BRACE FOR FORMS FOR CONCRETE WALLS.

Application filed January 4, 1921. Serial No. 434,987.

To all whom it may concern:

Be it known that I, RAY A. McHALE, a citizen of the United States, and a resident of Syracuse, in the county of Onondaga, and State of New York, have invented a certain new and useful Aligning Brace for Forms for Concrete Walls, of which the following is a specification.

This invention has for its object a particularly simple and efficient brace for aligning and holding the walls of forms for concrete walls, pillars, etc., at their bases, which brace is readily placed in the foundation or bed for the wall, pillars, etc., and is particularly simple in construction and economical in manufacture. The invention consists in the novel features and in the combinations and constructions hereinafter set forth and claimed.

In describing this invention, reference is had to the accompanying drawings in which like characters designate corresponding parts in all the views.

Figure 1 is a sectional view of a form and the foundation or bed, a pair of my braces being shown therein.

Figure 2 is a perspective view of one form of brace.

Figure 3 is a detail view of another form.

Figures 4 and 5 are detail views of a third form thereof.

This brace comprises generally, a body having upright and horizontal surfaces for engagement respectively with the inner faces of the lower margins of the walls of the form and with the upper face of the bed, and a depending prong for entering the bed.

1 designates the brace having an upright surface 2 and a horizontal surface 3 for engaging respectively the inner face of the lower margin of a wall 4 of the form and the upper face of the bed or foundation 5 which is usually cement. 6 designates the prong, this prong being preferably arranged with one edge 7 in alignment with the face 2, and with its other edge inclined and meeting the face or edge 3.

The brace is preferably formed of sheet metal and the face 2 is provided on a fold

or flap 8 while the face 3 is on the lower edge 50 of a flap 9 arranged at a right angle to the fold or flap 8.

The straight or vertical edge 7 of the prong 6 is in alignment with the plane of the outer face of the flap 8 and the inclined edge of 55 the prong meeting the lower edge 3 of the flap 9.

In Fig. 3, the flap or fold 9 is shown as formed with a horizontal flap 10 for resting on the surface of the bed and in Fig. 4 60. the flap 8 is omitted, the upright bearing face 2 being provided on the outer edge of the flap 9. Also in Figs. 4 and 5, the flap 9 is also provided with a flap 11 similar to the flap 10, Fig. 3, and the flap 11 is provided 65 with a downturned prong 12 for entering the bed 5.

In operation, these braces are first inserted in the bed along the lines the walls 4 of the mold are to rest and thereafter the walls of 70 the form placed with their lower margins against the braces, these walls being held together by the usual tie braces.

What I claim is:

1. In an aligning brace for forms for concrete walls, comprising a one piece sheet metal body formed with a prong for entering a foundation or bed for the wall, a surface for resting on the face of the foundation and a vertical face for engaging the inner 80 face of the wall of the form, the last-mentioned face and one edge of the prong being in vertical alignment, substantially as and for the purpose described.

2. An aligning brace for forms for concrete walls comprising a sheet metal body having upright folds arranged at a right angle to each other, one of said folds being arranged to abut against the inner face of the lower margin of the wall of the form 90 and the other to rest at its lower edge on the face of the foundation or bed for the concrete wall, the brace also having a depending prong having one edge thereof in alignment with the former fold and its other edge inclined and meeting the lower edge of the latter fold, substantially as and for the purpose set forth.

3. An aligning brace for forms for concrete walls comprising a body having an upright bearing surface, and a horizontal bearing surface for coacting respectively with the lower margin of the wall of the form and with the upright face of the bed or foundation for the concrete wall and also having a depending prong having one edge

thereof in line with the upright surface, substantially as and for the purpose described. 10

In testimony whereof, I have hereunto signed my name, at Syracuse, in the county of Onondaga, and State of New York, this 30th day of November, 1920.

RAY A. McHALE.
